FOREIGN PATENT DOCUMENTS

EP 2416049 2/2012

Primary Examiner — Angela J Lee(74) *Attorney, Agent, or Firm* — Michael Best & Friedrich LLP(57) **CLAIM**

The ornamental design for a tablet mount, as shown and described.

DESCRIPTION

FIG. 1 is a front perspective view of an embodiment of the design;

FIG. 2 is a front view of FIG. 1;

FIG. 3 is a rear view of FIG. 1;

FIG. 4 is a right side view of FIG. 1;

FIG. 5 is a left side view of FIG. 1;

FIG. 6 is a top view of FIG. 1;

FIG. 7 is a bottom view of FIG. 1;

FIG. 8 is a front perspective view of a second embodiment of the tablet holder with retaining arms extended.

FIG. 9 is a front view of FIG. 8;

FIG. 10 is a rear view of FIG. 8;

FIG. 11 is a right side view of FIG. 8;

FIG. 12 is a left side view of FIG. 8;

FIG. 13 is a top view of FIG. 8; and,

FIG. 14 is a bottom view of FIG. 8.

The retaining arms are shown broken away because no particular length is claimed.

1 Claim, 10 Drawing Sheets(56)
